UNITED STATES PATENT OFFICE.

FOSTER NOWELL, OF LOWELL, MASSACHUSETTS.

IMPROVEMENT IN WOOL-CARDING MACHINES.

Specification forming part of Letters Patent No. 15,016, dated June 3, 1856.

To all whom it may concern:

Be it known that I, FOSTER NOWELL, of Lowell, in the county of Middlesex and State of Massachusetts, have invented certain new and useful Improvements in Condensing Roving from Carding-Machines; and I do hereby declare that the following is a full and exact description thereof.

The description of carding-machines to which my improvements are applicable is that in which the doffer-cylinders are covered alternately with rings of card-clothing and vacant spaces of equal width. The wool or other material on the rings of card-clothing is to be gathered into roving, and to accomplish this object it is common to use tubes through which the strand of roving is drawn, and by giving the tubes a high velocity of revolution the strand is gathered into roving as it is drawn through the tubes. It is also common to use what are termed "rubbers," which ordinarily consist of a roll of the length of the doffer-cylinder, and which is made to revolve in a direction to draw the roving from the doffer. Above this roll, and resting upon it, are two other similar rolls, which have given to them a positive motion forward and back in the direction of their axes, and which receive from their contact with the lower roll a revolving motion. The roving is passed between the upper vibrating rolls and the lower rotating rolls and receives its condensing, so that when the roving is delivered from between the rolls it is in the form of a round strand suitable to be wound upon a spool without danger of its becoming entangled with other strands when it is unwound from the spool to be spun into yarn.

Both these processes effect the purpose to a certain extent, but have defects in operation and result, and it is the object of my improvements to control such defects.

In the use of rubbing and drawing rolls the roving is only acted upon while between the bite of the rolls, which of course extends only through a short length on the roving, and the ends of the fibers not being held at the same time with any considerable part of their length are not sufficiently tucked into the body of the roving by the condensing action. In all carding-machines using any condensing apparatus consisting of rubbing-rolls there are several strands which pass between the same rolls,

being at intervals in their length, and as the rolls all have rigid surfaces, if the strands are not of the same size, or if by accident two strands should come together, the surfaces of the rolls would not bear with a proper degree of force upon some of the strands, and the condensing would not be properly done. From the fact that the roving is acted upon only at the point of the bite of the rolls it becomes necessary to give a very quick vibratory motion in order to condense as much roving as the card is capable of working, and in some cases a vibration of two hundred and fifty times per minute has been found to be insufficient, but by increasing the number of rolls this has been partially remedied at the expense of more parts and greater wear.

My improvements consist in the use of two surfaces, one of which is rigid and the other yielding, between which the sliver is conducted and condensed, by which means the strands are all acted upon, notwithstanding they may be of unequal size, and in the form of these surfaces the sliver is made to be held and acted upon by them at one time to the extent, in the length of the sliver of six, eight, or ten inches, which is more than the length of ordinary fibers of wool.

In the accompanying drawings, Figure 1 represents an end elevation of the right-hand end of my apparatus. Fig. 2 represents a front elevation with the lower rubbing-cylinder in section. Fig. 3 represents an end elevation of the left-hand end.

The same letters refer to the same parts in all the figures.

A, Fig. 1, is the main cylinder of the card, and B B the ring doffer-cylinders, which are constructed in the usual manner. The working-cylinders, fancy cylinders, feeding-rolls, and many other parts are not represented, and will not be described, as they are not essential to a clear understanding of my improvements.

The doffer-cylinders, as is well known, have card-teeth in rings from one-half an inch to two inches in width, according to the work being done, and then a space of the same width, alternately, the card-teeth on the upper doffer being opposite the spaces on the lower one, and vice versa. The upper doffer takes from the main cylinder all the wool which is opposite to its rings of card-teeth, and the lower doffer takes the remainder. Thus the rings of

card-clothing on both doffers are continually supplied with wool, and the object of the apparatus is to gather this wool into suitable strands of roving that it may be spun into yarn.

On the shaft of the main cylinder of the card there is a bevel-gear, C, which drives other ones, D, F, and G, thus moving the crank-shaft H. This crank-shaft has at each end a disk, into which are inserted crank-pins I I. Crank-rods J J connect the crank-pins with the boxes K K, as shown in section on Fig. 3. This arrangement gives an end-long vibratory motion to the rubbing-cylinders L L.

On the left-hand end of the card, Fig. 3, the doffer-cylinders are driven in the direction designated by the arrows by means of the belt M and the spur-wheels O O. Similar spur-wheels, P P, are put upon the shafts of the rubbing-cylinders L L, but are not fastened to them; but the spur-wheels have a spline-groove, and the shafts have in them a spline, which arrangement allows the shaft to have an end-long movement in the hub of the spur-wheel, but will not allow the wheels P P to revolve without revolving the rubber-cylinders L L. The wheels O and P are of the same size; but I make the rubber-cylinder a little larger in diameter than the doffer-cylinder B B, in order that the roving may be stretched or drawn a little.

By the mechanism last described the rubbing-cylinders L L are made to revolve, and by the mechanism at the right-hand end, previously described, they are made to vibrate in the direction of their axes, thus having two distinct positive motions, one rotary and the other vibratory.

The surfaces of the rubber-cylinders are covered by winding closely about them cotton banding or cord, which produces an indented and somewhat rough surface, and more readily acts to roll the sliver than a leather surface.

Two rolls, R R, (of the same length as the doffer-cylinder and two or three inches shorter than the rubbing-cylinders L L,) are supported in bearings S S, and one is driven by means of gears, as shown at U in red ink, Fig. 3. These rolls have around them a belt or apron,

T T, the upper part of which extends in a straight line from the top of the roll to the top of the other, and the lower part of the belt takes the form of the curve of the outside circumference of the rubbing-cylinder. This belt is moved by the geared roll R. In the circumference of the rolls R R, and near each end, I cut a groove about one inch wide, and on the inside of the aprons I fasten strips of leather, so that they will run in the grooves and keep the belt from vibrating on the rolls and hold it in place. The rolls nearest to the doffer-cylinders are adjusted so that the outside of the apron will just clear the ends of the teeth of the doffer-cylinder, and the other roll is placed so as to give the requisite form and tension to the apron. As the wool on the rings of card-clothing of the doffer comes to the apron on the rolls R R the apron wipes it off from the rings in the form of ribbons or slivers and conducts it between the apron and the rubbing-cylinder, where by the vibration of the rubbing-cylinder they are each gathered and rolled into a round strand of roving, and afterward ejected from between the rubbing-cylinder and the apron in a condition suitable to be wound upon spools in the usual manner; and from the working of a machine constructed after this manner I find that the number of vibrations necessary with the long frictional surface between the belt and the rubbing-cylinder is about one-fourth of the number of vibrations with the use of rubbing-rolls in the method now in common use.

Having thus described my improvements and the mode of operating them, what I claim as new, and desire to secure by Letters Patent, is—

The use in carding-machines of two surfaces for conducting and rubbing the sliver from the ring-doffers, one of which is cylindrical and of permanent form and the other a belt or apron of flexible material and capable of adjusting itself to the shape of the cylindrical rubber and the sliver or roving between itself and the cylindrical rubber, substantially as described.

FOSTER NOWELL.
